ABSTRACT

A screen of alternately oriented accordian folds opens out for display of small objects placed on support points or shelves thereon.

1 Claim, 2 Drawing Figures

PATENTED JUL 23 1974

3,825,216

FIG. 1

FIG. 2

FOLDING DISPLAY

This invention relates to ornamental objects in the display arts, more particularly to objects used in a substantially vertical arrangement.

A principal object of this invention is to provide a collapsible, self-standing, screen-like form for artistically disposing thereon objects to be displayed.

Another object of this invention is to provide a display form that occupies a small packaging space yet when opened up for use gives an impression of solid geometric form thereby adding attractively to the display of objects thereon.

These and other objects will be readily evident upon a study of the following specification together with the accompanying drawing wherein:

FIG. 1 is a perspective view of the display form;

FIG. 2 is a perspective view of a device that may be used for adding to the rigidity of the form of FIG. 1.

Collapsible display forms used in the art have been unsatisfactory for one or more reasons. They are complicated to set up or collapse or are costly per unit when made attractive or look like collapsible stands when made cheap. The present invention will show that a display form may be made collapsible yet look solid and attractive, the form is easy to set up or take down and all at a low cost.

Referring to FIG. 1 the display form 10 shows a sheet of material 11 that is folded along the vertical boundaries of the display area as at 12. The folded material 11 is seen bent back as at 13 and there extending to a vertical corner by another pair of bends at 14. The remaining material 11 forms two panels 15 and 16 which overlap and are placed in contact as seen at 17.

The display area of material 11 is prepared by making a series of horizontal staggered cuts from a point 18a to a point 18b. When all the cuts for a predetermined pattern have been made, material 11 is folded in an alternating manner so as to produce an inside fold 19 and outside fold 20 below cut 18 and an inside fold 21 above cut 18. The resulting effect as seen in FIG. 1 is a cubic-like accordian pattern. It becomes evident that this display may be extended from its col-

lapsed position to any degree that will serve its display purpose. If the folds are intended to be shallow, it becomes obvious that panels 15 and 16 need only be deeper in order to overlap at 17.

The edges 22 exposed by cuts 18 may be used for hanging the objects to be displayed. Alternately shelves may be placed on edges 22, such shelves then serving as horizontal display areas.

Any means known in the art may be used for securing 10 panels 15 and 16 against relative movement. An alternate means that eliminates a need for attaching devices between panels 15 and 16 is shown in FIG. 2. A double-T structure 23 comprises a member 24 having attached 15 at the ends a pair of channels 25. By merely slipping channels 25 over the top edges of side panels 13 panels 15 and 16 become immobilized so that the whole structure is rigid.

What I claim is:

1. A folding display device consisting of a configurated member and a retaining member, said configurated member being formed from a rigid sheet material having a plurality of full length vertical folds to form a front wall, opposite side walls, parallel to each other and a rear wall, said front wall being formed by a center portion of said sheet while said rear wall is formed by opposite side end folded panels being joined together, said side walls being at right angle to said rear wall, and said front wall having a plurality of spaced apart horizontal cuts between which there are a plurality of vertical fold lines forming right angle folding bends, thus forming a plurality of spaced apart, forwardly and rearwardly projecting portions, each alternate projection extending forwardly while each projection there between extends rearwardly, and said retaining member comprising an H-shaped element having a pair of parallel spaced apart, side channels which at their longitudinal centers are interconnected by a cross member, each of said side channels being of inverted cross sectionally U-shaped configuration in order to be 30 clipped over the upper edges of said configurated member side walls so retain said configurated member.
